UNITED STATES PATENT OFFICE.

JOSEPH WESTENHUBER AND ANTON WEHRLE, OF TOLEDO, OHIO.

METHOD OF FORMING HOLLOW CONCRETE BODIES.

No. 838,226.

Specification of Letters Patent.

Patented Dec. 11, 1906.

Application filed April 25, 1906. Serial No. 313,546.

To all whom it may concern:

Be it known that we, JOSEPH WESTENHUBER and ANTON WEHRLE, citizens of the United States, and residents of Toledo, in the county of Lucas and State of Ohio, have invented a certain new and useful Method of Forming Hollow Concrete Bodies; and we do hereby declare the following to be a full, clear, and exact description of the invention, such as will enable others skilled in the art to which it appertains to make and use the same, reference being had to the accompanying drawings, and to the figures of reference marked thereon, which form a part of this specification.

Our invention relates to the manufacture of reinforced concrete articles, and particularly to the construction of hollow bodies having cylindrical, octagonal, or similar shaped contours—such, for instance, as eisters, tile, vaults, or the like.

The object of our invention is to provide a cheap and simple method of manufacturing articles of this class, whereby the contour of the article formed may be made in any suitable shape and substantially reinforced and the article itself when completed and dried be capable of withstanding heavy strains and hard usage.

The invention is fully described in the following specification, and one form of embodiment thereof illustrated in the accompanying drawings, in which—

Figure 1 is a perspective view of a bed employed in the carrying out of our invention with the outer forming plate or sheet positioned therein and covered by a layer of concrete or other suitable plastic material. Fig. 2 is a longitudinal vertical section of the same on a reduced scale, with the outer forming-sheet and superimposed plastic material shown as partially rolled around a forming mandrel or inner mold-body, which carries the reinforcing means. Fig. 3 is a perspective elevation of a formed cylinder with the outer and inner forming members partially removed therefrom. Fig. 4 is a perspective view of the removable adjusting-core of the inner mold-body or mandrel. Fig. 5 is a perspective view of the inner forming cylinder or member with the reinforcing member encircling it; and Fig. 6 is a perspective view of a portion of the concrete body, showing its inner surface plastered over.

Referring to the drawings, 1 indicates the molding-bed in which the concrete blank is

first formed. This bed is of the proper shape and size to suit the required formation of the blank. In the bottom of this bed is placed the outer molding-sheet 2, of flexible material, which covers the bottom thereof and has its end edges turned down at right-angles, as shown at 3, and provided with either perforations or slots 4 for the purpose herein-after described. Upon this sheet is placed a layer of concrete or other suitable plastic material 5 of the desired thickness, as shown in Figs. 1 and 2. The ledges 1^a at the sides of the bed 1 are preferably of a depth equal to the combined thickness of the mold-sheet 2 and concrete 5, so that after the concrete has been packed therein a leveling-tool may be passed across the top of the bed to level the surface of concrete.

The inner mold-body or mandrel, about which the concrete is formed into the desired shape, comprises a flexible metal sheet 6, which is formed into the shape desired to be assumed by the interior of the body to be molded and has its meeting edges loosely lapped, as shown at 7 in Figs. 3 and 5, to permit of a contraction or expansion thereof. Within this molding-sheet is mounted a removable adjusting core or member 8, which is shown as consisting of an axially-disposed hub portion 9, from which radiate a plurality of spaced sets of arms 10, the outer ends of which are designed when turned within the inner mold member 6 to coact with alining cam plates or surfaces 11, thus causing an expanding or tightening of the member 6 within the part 12, forming the reinforcement for the body to be formed. The cam plates or surfaces 11 are secured by rivets 13 or in any other suitable manner to the inner surface of the member 6, as shown. The part 12, forming the reinforcement of the body when molded, consists of any suitable material having a rough, perforated, or irregular surface—such, for instance, as wire fabric, corrugated or perforated sheet metal, or the like. This material is rolled into cylindrical or other desired form, either around the inner mold-body or separate therefrom, and has its meeting ends fastened together, as at 14 in Fig. 5. We wish it to be understood that we do not desire to be limited to the exact details of construction of the parts above described and shown, for obvious modifications will occur to a person skilled in the art.

In the forming of the plastic blank 5 into a hollow body of the desired shape the inner

mold member 6, with the reinforcing material 12 encircling it and the adjusting core or member 8 tightened therein, so that the member 6 is held against contraction due to the application thereto of external pressure, is placed upon said blank, at one end thereof, and the concrete 5 and outer molding-sheet 2 at such end, then held firmly to the surface of the mold while it is rolled over the blank to the other end thereof. This operation causes the layer of concrete 5 and flexible molding-sheet 2 to be wrapped around the mandrel or inner molding-body with the sheet 2 forming the inclosing casing and the inner surface of the plastic material adhering to the rough or irregular surface of the reinforcing member 12. The lengths of the plastic blank 5 and molding-sheet 2 are properly proportioned relative to the mandrel or inner molding-body to enable them to reach entirely around said mandrel or body and their ends to squarely abut, as shown by dotted lines in Fig. 2, and are firmly secured in such position by bolts 15 or other suitable means, binding the flanges 3 at the ends of the sheet 2 together. The drawing of the ends of the molding-sheet 2 together causes the ends of the plastic blank to closely adhere to each other and the inner surface thereof to be compressed within the meshes, perforations, or irregularities of the reinforcing material. This being done the body thus formed is allowed to dry. It is preferable to leave the inner molding body or mandrel in the formed article during the drying operation, or at least until the concrete becomes sufficiently set to maintain its shape. The outer sheet 2 is removed from the article by simply removing the bolts or other retaining means from the flanges 3 thereof, thus permitting it to be unwrapped from the molded body, as shown in Fig. 3, while a removal of the inner mold-body is accomplished by turning the core 8 until the ends of the arms 10 thereof are loosened from the cam-surfaces 11, as shown by dotted lines in Fig. 2, thus permitting the core to be easily withdrawn. The inner molding-sheet 6 is slightly compressed to permit its easy removal from within the reinforcing member 12, which adheres to the concrete and forms the lining of the molded article.

If desired, the interior of the molded body may be covered with a coat of concrete or plaster to form a smooth inner surface, as shown at 16 in Fig. 6, in which case the reinforcing material forms a surface to which the plaster readily adheres.

Having thus described our invention, what we claim as new, and desire to secure by Letters Patent, is—

The method of forming hollow concrete bodies consisting of first wrapping a porous reinforcing member about the forming-mandrel and securing its ends together, then wrapping a flexible sheet and superimposed plastic blank about the reinforcing member and mandrel and securing the ends of the sheet together with the ends of the plastic blank in abutment, then allowing the blank to become set after which the sheet and mandrel are removed.

In testimony whereof we have hereunto signed our names to this specification in the presence of two subscribing witnesses.

JOSEPH WESTENHUBER
ANTON WEHRLE.
